CLAIM

The ornamental design for a test meter, as shown and described.

DESCRIPTION

FIG. 1 is a front perspective view of the test meter; FIG. 2 is a rear perspective view of the test meter; FIG. 3 is a front elevational view of the test meter; FIG. 4 is a rear elevational view of the test meter; FIG. 5 is a left side elevational view of the test meter; FIG. 6 is a right side elevational view of the test meter; FIG. 7 is a top plan view of the test meter; and, FIG. 8 is a bottom plan view of the test meter. The broken lines showing the numerical expression in the liquid crystal display in FIG. 1 is for the purpose of illustrating unclaimed portions of the design and forms no part of the claimed design.
